UNITED STATES PATENT OFFICE.

EDWARD S. STIMPSON, OF HOPEDALE, MASSACHUSETTS, ASSIGNOR TO DRAPER COMPANY, OF HOPEDALE, MASSACHUSETTS, A CORPORATION OF MAINE.

TENSION FOR LOOM-SHUTTLES.

1,103,097.

Specification of Letters Patent. Patented July 14, 1914.

Application filed August 2, 1912. Serial No. 712,878.

To all whom it may concern:

Be it known that I, EDWARD S. STIMPSON, of Hopedale, in the county of Worcester and State of Massachusetts, have invented a new and Improved Tension for Loom-Shuttles, of which the following is a specification.

The present invention consists in an improvement upon the character of tension for loom shuttles which is set forth in United States Letters Patent of Samuel B. Cutting, No. 727,594, dated May 12, 1903.

In accordance with the present invention, the weft thread on its way from the weft-carrier within the shuttle to the shuttle-eye passes between a relatively stationary tension surface and a spring-pressed tension member which applies the requisite tension to the thread and which permits the ready automatic threading of the shuttle.

The present improvement is illustrated in the accompanying drawings, in which—

Figure 1, is a plan view of the eye end of an automatically threading shuttle. Fig. 2, is a longitudinal section in the plane indicated by the line 2—2 in Fig. 3. Fig. 3, is a cross-section in the plane indicated by the line 3—3 in Fig. 1. Fig. 4, is a view of the eye end of the shuttle from the side opposite to where the eye is located. Fig. 5, is a perspective view of the several specific devices which are associated together to give tension to the thread.

The improved shuttle tension is shown as applied to an automatically threading shuttle which is substantially similar to that shown in United States Letters Patent, No. 933,497, dated September 7, 1909.

The shuttle A, has a threading chamber B, at its eye-end in which is located a sheet metal threading device of the character described in said Patent, No. 933,497. As in that patent, this sheet metal threading device comprises separated vertical side walls C, D, a beak E, at the front which directs the thread to the eye F, of the shuttle, a guard G, at the front which overhangs the beak, a guard H, at the rear of the thread passage M, which retains the thread in the thread passage between the two side walls of the threading device. The wall C, is at the front or eye side of the shuttle and the wall D, is at the opposite or rear side of the

shuttle. The threading device is held in place by means of a transverse bolt I, which extends through apertures in the shuttle body and apertures J, in the walls of the threading device, this bolt screwing into a nut K, countersunk in the rear side of the shuttle body, as shown in Fig. 4. In all of these respects the construction is substantially that of said Patent No. 933,497.

The purpose of the present invention is to automatically apply tension to the thread as it passes from the weft-carrier L, through the thread passage M, to the eye F. The tension device consists of two members, a stationary abutment N, and a transversely movable presser O. The stationary abutment N, is constituted by the front vertical wall of a metallic channeled tension block P, which fits within the thread passage M, and which has a transverse hole Q, through which the bolt I, passes, thereby holding the channeled block in place. The central channel R, of this block constitutes a portion of the thread passage M, through which the thread passes. The front wall or abutment N, is beveled at its forward edge as shown at S, in Fig. 5, and around this the thread passes to the shuttle-eye F. The abutment N, has a vertical recess T, shown in Fig. 5, which is opposite a vertical guide slot U, in the opposite wall of the tension block P. This slot U, constitutes the guide slot for the presser O, which extends into said guide slot and also through a guide aperture V, in the rear wall D, of the threader. The presser O, is pressed toward the recess T, of the abutment N, by means of a spring W, which is adjustably held in place by a shoulder screw X, which screws into the nut K. The presser is thus yieldingly held against the abutment encountering the margins of the recess T. The presser is beveled and rounded at its upper corner, adjacent to the abutment N, as shown at Z, thereby presenting a flaring entrance for the thread. As the thread is drawn through the thread passage M, R, to the eye F, beneath the beak E, it rides down the beveled corner Z, of the yielding presser O, and is frictionally held by the presser O, pressing it against the abutment at the margins of the recess T. This is done automatically when the shuttle threads itself or is threaded. The spring W

acting on the presser O, maintains the proper tension upon the thread during the running of the shuttle.

I claim:—

5. 1. An automatically threading shuttle having, in combination, a sheet metal threader having a longitudinal thread passage with a slot in its side wall opposite the slotted shuttle eye; a longitudinally channeled tension block fitting in said thread passage with a guide groove in its wall opposite the shuttle eye and registering with the slot in the threader wall, said tension block also having an abutment on the side adjacent to the shuttle eye and a vertical recess in the abutment facing the guide groove; a spring-pressed presser fitting in said guide groove and in the slot of the threader and adapted to press the thread against the abutment and into the vertical recess thereof, the top of said presser being adapted to direct the thread toward the abutment; a nut in a recess in the shuttle body opposite the presser; an adjusting screw fitting in said nut; a spring between the screw and the presser; and a single transverse bolt passing through both the threading device and the tension block and holding them in place.
30. 2. An automatically threading shuttle having, in combination, a threader having a longitudinal thread passage with a slot in its side wall opposite the slotted shuttle eye; a longitudinally channeled tension block fitting in said thread passage with a guide groove in its wall opposite the shuttle eye and registering with the slot in the threader wall, said tension block also having an abutment on the side adjacent to the shuttle eye and a vertical recess in the abutment facing the guide groove; a spring-pressed presser fitting in said guide groove and in the slot of the threader and adapted to press the thread against the abutment and into the vertical recess thereof.

and in the slot of the threader adapted to press the thread against the abutment and into the vertical recess thereof; and a single transverse bolt passing through both the threading device and the tension block and holding them in place.

3. An automatically threading shuttle having, in combination, a threader having a longitudinal thread passage with a slot in its side wall opposite the slotted shuttle eye; a longitudinally channeled tension block fitting in said thread passage with a guide groove in its wall opposite the shuttle eye and registering with the slot in the threader wall, said tension block also having an abutment on the side adjacent to the shuttle eye and a vertical recess in the abutment facing the guide groove; and a spring-pressed presser fitting in said guide groove and in the slot of the threader adapted to press the thread against the abutment and into the vertical recess thereof.

4. An automatically threading shuttle having, in combination, a threader having a longitudinal thread passage with a slot in one of its side walls; a longitudinally channeled tension block fitting in said thread passage with a guide groove in its wall registering with the slot in the threader wall, said tension block also having an abutment opposite said groove; and a spring-pressed presser fitting in said guide groove and in the slot of the threader and adapted to press the thread against the abutment.

In witness whereof, I have hereunto signed my name in the presence of two subscribing witnesses.

EDWARD S. STIMPSON.
